(57) CLAIM

The ornamental design for a bag as shown and described.

DESCRIPTION

The file of this patent contains at least one drawing/photograph executed in color. Copies of this patent with color drawing(s)/photograph(s) will be provided by the Office upon request and payment of the necessary fee.

1. Bag

1.1 : Perspective

1.2 : Front

1.3 : Back

1.4 : Right

1.5 : Left

1.6 : Top

1.7 : Bottom

1.8 : Enlarged detail view taken from 1.9

1.9 : Perspective in Open Configuration

The characteristic features of the design lie in the combination of the shape and decorative rings of three different colors on the sides of the bag; protection for color is claimed.
